2 SHEETS-SHEET 2.

UNITED STATES PATENT OFFICE.

WILLIAM A. DUNN, OF SMITHVILLE, MINNESOTA, ASSIGNOR OF ONE-HALF TO ATHOL MORTON MILLER, OF DULUTH, MINNESOTA.

STEEL STRUCTURE.

974,779.

Specification of Letters Patent. Patented Nov. 8, 1910.

Application filed April 19, 1910. Serial No. 556,821.

To all whom it may concern:

Be it known that I, WILLIAM A. DUNN, a citizen of the United States, residing at Smithville, in the county of St. Louis and State of Minnesota, have invented certain new and useful Improvements in Steel Structures, of which the following is a specification.

My invention relates to improvements in the manufacture of compartments, and particularly to the hulls of ships.

According to my improvements I employ specially rolled steel plates, beams, and ribs, and secure the same together to dispense with a superstructure, my purpose being to form the plates with ribs which will serve as a strengthening medium, in lieu of separate bars or frame work usually employed to perform this function.

The invention also comprehends improvements in the specific details of construction and arrangement of parts to be hereinafter described, and particularly pointed out in the claims.

In the drawings: Figure 1 is a perspective sectional view of the hull of a vessel constructed in accordance with my invention. Fig. 2 is a detail sectional perspective view, illustrating part of the side and deck of the hull. Fig. 3 is a similar view of a modified form of the invention. Fig. 4 is a similar view of a further modification. Fig. 5 is an enlarged detail sectional view of a beam, used as a keelson. Fig. 6 is a detail horizontal perspective section of the plates showing a slightly different arrangement. Fig. 7 is a detail view of a stepped keelson.

The same numerals refer to like parts in all the figures.

1 indicates one of a series of outside plates, formed with inwardly extended ribs or flanges 2, which are located a short distance from opposite ends of each of the plates. These plates may be formed with or without two ribs or flanges 2, according to the circumstances, or the character of the compartment to be constructed. For instance, in Figs. 1 and 2, the flanges are disposed near each edge of the plates, while in Fig. 4,

I show the plates with a flange 2^a, at or near one edge only, and in Fig. 3, the said flanges 2^b are located at the extreme end of each plate, the face of each flange being flush with the end of the plate.

According to my invention I employ, with

the plates 1, beams 5 which may be laid in the bottom of a vessel to support braces or bulk heads, if desired. One of these beams indicated at 6, is employed as a keelson, and is adapted to overlap the adjacent meeting ends of the plates 1.

I assemble with the plates and beams a series of channel plates or beams 15 each being formed with end flanges 16, extending from the web. The plates or beams being primarily designed for the deck of the boat, as will be hereinafter described.

To illustrate one use of my invention, I have illustrated the hull of a ship made up of my improved plates and beams but it is to be understood that this is in no way a limitation as to the use to which the improvements may be employed, as it is evident, compartments of various types can be constructed in the same effective manner, particularly where strength, economy and durability are essential requisites.

In Fig. 1 the plates 1 are shown in assembled form, to provide the hull of a boat. The plates forming the outside of a hull (or compartment, as the case may be) incline somewhat toward the bottom, the bottom of each plate overlapping the upper edge of the next succeeding plate, as indicated at 8. A row of rivets 9 secure the overlapping portions of the plates together and the joints are suitably calked to render the hull watertight. These plates are placed end to end throughout the length of the hull the edges of the plates abutting, and overlapping the inside of the joints between the abutting edges are thin flat rolled steel plates 10, riveted to the adjacent plates 1—1 as shown at 11.

By reference to the drawing, it will be seen the ribs or flanges 2, project inwardly, and serve as reinforcing braces to strengthen the structure throughout its entire length. The abutting edges of the ribs or flanges are also overlapped by plates 20, suitably riveted, to insure stability of the structure.

The vertical joints formed between the adjacent plates are calked, in any approved manner.

In the center of the bottom of the hull is the longitudinal I beam 6. Several such beams may be connected together and riveted according to the length of the boat and they run the full length of the structure to strengthen the same as shown in Fig. 7.

Other beams 5 of different heights may be located each side of the keelson to provide supports for the interior superstructure of the boat.

5 The deck, or top of the hull is formed by assembling the channel plates or beams 15, with their flanges 16; abutting as shown in Figs. 1 and 2. These plates when assembled are arranged end to end, the flanges extending inwardly, and the latter are riveted together as indicated at 17, the outermost flanges 18 of the outside plates 15 being riveted to the upper end of the side plates 1, as at 19. The adjacent flanges and ends of 15 the deck plates are secured together by overlapping plates 20. The flanges 16, provide not only a means for securing adjacent channel plates together, but in addition thereto, they produce a plurality of reinforcing longitudinal ribs, producing a strong and stable 20 deck structure. To further strengthen the deck structure formed by the plates 15, I provide a series of I beams 21, under the ribs or flanges 16, and may be secured to the 25 latter by overlapping metal plates 23. The joints of the deck are calked to make the same water tight.

By dispensing with a flange, or rib at one edge of each plate, the overlapping of two 30 adjacent plates occurs opposite to the rib or flange on the next succeeding plate, as shown in Fig. 4. The overlapping portions of the plates when arranged as shown in this figure will be riveted on both sides 35 of the rib 24. Thus the structure is doubly reinforced throughout its entire length.

By constructing a hull, or compartment, or other structure, in the manner described, it will be obvious the same is extremely 40 economical as it is not necessary to provide a separate super-structure. The flanges or ribs of the plates 1 and 15 serve to brace the hull, in precisely the same manner as if applied in separate pieces. It may be stated 45 as a fact, that flanges made integral with the plates possess decided advantages over separate pieces, inasmuch as liability to break or separation between the braces and plates is impossible. Furthermore, thelapping of the plates at points adjacent the flanges or ribs, adds materially to strengthen the structure, and reinforces the flanges.

It will be obvious, I may arrange the plates so that they may overlap each other 55 in vertical alinement, as shown in Fig. 6, rather than in horizontal alinement, as shown in the other figures of the drawing.

The keelson may be formed by placing beams of different height, end to end, as 60 shown in Fig. 7. It is essential to make the keelson heavier where the engines, or other heavy mechanism is supported in the hull of a boat, and so far as I am aware, heretofore it has been necessary to build up a 65 beam for this purpose. But I find that I

can accomplish the desired result by tying together two or more beams, 6 each of different height, and each being formed in a separate piece.

A hull of a boat made up of plates and 70 beams, in addition to strength, possesses lightness, as the interior superstructure usually employed is entirely dispensed with.

The plates may be of any convenient width, length and thickness, depending entirely upon the character of the structure formed.

What I claim is:

1. A compartment formed of a plurality of plates having integral ribs, the edges of 80 said plates overlapping the edges of the adjacent plates, means for securing the overlapping portions of the plates together, the other edges of the plates abutting against the edges of the plates adjacent thereto, the 85 ribs of the adjacent plates whose edges abut being in alinement to provide braces for the compartment and a beam located at the bottom of the compartment and overlapping the meeting edges of the plates. 90

2. A compartment formed of a plurality of plates having integral ribs, the edges of each plate overlapping the adjacent plate, rivets securing the overlapping portions of the plates, the other edges of said plates being placed end to end and the ribs of adjacent sections being in alinement to provide braces for the compartment, and a beam located at the bottom of and extending throughout the length of the compartment 100 and overlapping the meeting edges of the plates.

3. A compartment formed on its sides and bottom by a plurality of plates formed with ribs, the adjacent edges of said plates overlapping at points adjacent the ribs, rivets securing the overlapping portions of the plates, the other edges of the plates abutting against each other and the ribs forming continuous reinforcing braces on the inside of 110 the compartment, plates overlapping the edges of the plates which abut against each other, rivets securing the latter plates, a series of channel beams forming the top of the compartment, the flanges of the channel beams abutting and forming reinforcing ribs throughout the length of the compartment, and rivets securing the said latter flanges together. 115

4. A compartment such as a ship's hull, comprising a series of plates having integral ribs extending inwardly from said plates, the edges of the plates overlapping and the edges of the plates extending inside bearing against one of the ribs of the next adjacent 125 plate, rivets securing the overlapping portions of the plates together, and a deck or cover formed of plates having flanges riveted together.

5. A compartment formed of a series of 130

plates formed with flanges at their edges, the said plates overlapping the adjacent plate, rivets securing the overlapping plates below the edge flanges, a series of channel plates forming the top of the compartment, the flanges of adjacent channel plates being arranged side by side and riveted, the flange on the uppermost side plate overlapping and being riveted to the end channel plate.

10. 6. A compartment comprising a series of side plates, each side plate having a flange at or near one edge and the adjacent edges of said side plates overlapping, a series of rivets above and below the flanges for securing the overlapping portions of the plates together, and a top for the compartment, said top comprising a series of channel plates, the flanges of adjacent channel plates abutting, and rivets securing the said abutting flanges together.

7. A ship's hull comprising plates to form the sides and bottom, each plate having inwardly projecting flanges located some distance from the edges, the edges of the plates overlapping the adjacent plates from the top of each side of the hull toward the bottom, a beam at the bottom forming a keelson, the overlapping plates at the bottom being secured to the beam, a deck comprising channel plates having inwardly extending flanges, rivets securing the flanges of

the adjacent channel plates together, the flanges on the outermost channel plates engaging the uppermost side plates, rivets securing the said side plates and end flanges together, and beams arranged transverse of the abutting flanges to form supports for the latter.

8. A compartment formed of a plurality of plates having integral ribs, the edges of each plate overlapping the adjacent plate, rivets securing the overlapping portions of the plates, the other edges of said plates abutting against the edges of adjacent plates and the ribs of adjacent plates being in alinement to provide braces for the compartments, reinforcing means located at the bottom and extending throughout the length of the compartment and overlapping the edges of the plates, said reinforcing means comprising beams each beam being formed from a single piece of metal, and each beam being different in height than the adjacent beam, and means for tying the beams together.

In testimony whereof I affix my signature in presence of two witnesses,

WILLIAM A. DUNN.
